UNITED STATES PATENT OFFICE.

HENRY ISMAY MORALEE ROSS, OF DUNEDIN, NEW ZEALAND.

BUILDING CONSTRUCTION.

Application filed October 31, 1921. Serial No. 511,708.

To all whom it may concern:

Be it known that I, HENRY ISMAY MORALEE Ross, a subject of His Majesty, the King of Great Britain, residing at Bond Street, 5 in the city of Dunedin, in the British Dominion of New Zealand, have invented certain new and useful Improvements in Building Constructions, of which the following is a specification.

10 The object of this invention is to set forth a rapid way of strong building construction, in which the bulk of the material consists of plain or reinforced concrete slabs having specially formed edges, and specially formed metal bars to suit these slabs, and the gist of the invention is, that these are prepared before being built in, as they can be readily fitted together expeditiously, thus eliminating the expensive "formes" 15 now used in concrete construction. The special bars are suitable for studs, joists and rafters, they are of girder form, some with two, and some with four unequal depth flanges on each side of a central web, and 20 others with such flanges on one side only. Also some with the above members or flanges but with a diagonal web. There are special bars and gripping bars for openings, such as windows. These would generally 25 be rolled to the desired shapes, and short lengths between such as openings, would be either cuttings, or might be cast to the shape. The concrete slabs have their edges moulded to suit each other and the metal bars for 30 which they are intended, and when placed in position, would be flushed with cement mortar, and could subsequently be given any architectural finish, inside or outside.

35 The specially formed metal bars for studs, plates, joists or rafters are secured together by bolts or other usual devices, forming the skeleton or frame of the building, the weight of any superstructure or roof is carried by the said framework and not by the concrete; so that when the frame is up, any 40 storey may be completed before the ground floor slabs are placed in position.

45 Referring to the accompanying drawing:—(2 sheets),

50 Figure 1 is the section of a building as in my invention, the 1st floor being shown with two descriptions of flooring, one of light, and the other of stronger construction.

55 Fig. 2 are sections of rafters, formed for

the concrete slabs to slide endwise between them as shown in Fig. 1.

Fig. 3 are sections for the slabs to be lowered sideways between them, these being suitable for flat surfaces or roofs. Fig. 4 60 is a sectional plan of upright studs, showing the slabs being placed between them, and Fig. 5 is a slight modification of the bars and consequently of the edges of the slabs to suit them.

65 The remaining are details to a larger scale. Fig. 6 is a plan through a fixed window showing the fixing of frames for holding glass to the special studs. Fig. 7 is an end section through a window showing its 70 fixing, and a short stud to foundation, and Fig. 8 is a part elevation of same. Fig. 9 is a section of an intermediate bar for fixing glass to, having a tubular core, and Fig. 10 is same but with a wood core. Figs. 75 11 and 12 to a still larger scale, show alternate ways of securing window frames to the studs, viz:—a light and a stronger way respectively.

A is an ordinary channel bar, sometimes 80 suitable for foundation but I often prefer an H or I bar on its side thus bedding the lower flanges in "green" cement concrete as see Fig. 7, between the upturned flanges or either of them, upright stud-bar 85 B would be secured at convenient distances, to suit the concrete slabs C, (see Figs. 4 and 5) B¹ is an end stud. B² is a modification in a somewhat Z section, and B³ is same, but of stronger make. These bars are 90 often of interchangeable use, as see Fig. 1 where stud-bars act as floor joists. C are concrete slabs whose edges that touch bars, fit them, and C¹ are same, but strengthened with expanded metal as shown, (or wire or 95 wire-netting,) which will extend beyond the moulded edges of the concrete slabs, forming a bond or tie between them, when they would be subsequently covered by cement plaster. Figs. 1, 3 and 4 show these being 100 placed in position, and Figs. 2 and 5 show them in position. Special sections for light joists D, and end ones D¹, rafters E, and end ones E¹ are shown.

105 It will be seen that B has a web and eight flanges of varying depths, four facing to the right and four to the left, the inner flanges being deeper than the outer ones for guiding the slabs into their proper grooves, also that the studs B B when in their places as shown, 110

have a deeper groove and a shallower one opposite each other, for enabling the slab C to be side-slipped into place one of its side edges being entered into the deeper groove first for the slab to clear the short flange of the opposite stud, when the slab is then slipped home into the shallow groove, and the superfluous space in the deeper groove between the slab and the stud is filled with cement mortar. Any bars may be spaced by light tubes between, F; with a bolt F¹ run through several. G is a form of brace and G¹ a tie for rafters as needed. H are glass gripping window-frames screwed together, either secured to half studs B¹ by bolts J, or a special bar K, or to a modified special bar K¹ as suited to B¹ and B, respectively. H¹ and H² are a pair of gripping window bars. H³ and H⁴ are similar ones but of stronger make. H⁵ are light ones for light work, being a horizontal bar in one piece. L is a tongue used as a finish at corners of window frames for ensuring a tight joint. It will be seen that the bulk of the materials can be formed beforehand and be placed in a condition for quick fixing, which, with the special shaped bars and slabs to fit same, form the gist of the invention. Any suitable sizes or materials may be adopted.

Having described the invention what I desire a patent of the United States of America for, is:—

1. In buildings mainly of concrete and metal, metal bars having deep and shallow grooves on their reversed sides, and each bar having a deep and a shallow groove, back to back on its outer and inner edges, so that when placed in position as a rafter, stud or joist, a deep groove will be opposite a shallow groove, irrespective of either edge being reversed in positioning the bars, combined with specially formed concrete slabs, shaped to suit the grooves and flanges of the said bars, metal reinforcement in said slabs, to form the key between the concrete slabs for the cement grouting and stopping which unites the whole wall as one piece, in com-

bination with bars connecting with said first named bar.

2. An article of manufacture consisting of a bar for use in building constructions, said bar having a deep groove on one side and a shallow groove on the opposite side. 50

3. An article of manufacture, a stud adapted to be used in groups of two or more in building constructions, said stud having deep grooves and shallow grooves arranged in pairs at diagonally opposite positions on said studs, each deep groove lying back to back with each shallow groove. 55

4. In a building construction, a plurality of studs having a shallow groove on one side and a deep groove on the opposite side, each deep groove of one stud lying opposite a shallow groove of the next adjacent stud, 60 slabs having tongues adapted to project into said grooves.

5. An article of manufacture, studs adapted to be used in groups of two or more in building constructions, said studs having deep grooves and shallow grooves arranged in pairs at diagonally opposite positions thereon, each deep groove lying back to back with each shallow groove, slabs having tongues adapted to project into said grooves 70 and a portion projecting beyond said studs. 75

6. In a building construction, a plurality of studs having a shallow groove on one side and a deep groove on the opposite side, each deep groove of one stud lying opposite a shallow groove of the next adjacent stud, 80 slabs having tongues adapted to project into said grooves and a portion projecting beyond said studs, and a filler extending into said grooves overlapping said studs and filling 85 the space between the slabs.

In testimony whereof I have hereunto set my hand in presence of two subscribing witnesses.

HENRY ISMAY MORALEE ROSS.
